UNITED STATES PATENT OFFICE.

GEORGE W. KECK, OF INDEPENDENCE, KANSAS.

SELF-SERVICE GASOLINE-PUMP ATTACHMENT.

Application filed December 31, 1925. Serial No. 78,565.

This invention relates to certain new and useful improvements in attachments for gasoline pumps of the type employed in connection with the dispensing of gasoline for motor vehicles and other uses and has for its primary object to provide a series of manually operative devices for feeding a predetermined quantity of gasoline to a dispensing receptacle or bowl and delivering the gasoline from the bowl to the customer with the operation of said devices being coin-controlled.

The invention relating to a self-service gasoline pump attachment that is controlled in its operation by a coin of a predetermined denomination, said invention embodies devices for detecting a false or counterfeit coin, such as a washer, and being constructed to prevent operation of the mechanism and discharge of the false coin to eliminate clogging in the mechanism.

The invention further embodies devices rendered operative in the presence of a coin to open a valve and permit the flow of gasoline from a storage tank into a delivery receptacle or bowl, such as in common use, with the overflow of gasoline through the stand pipe in the delivery bowl effecting the release of the supply valve to permit the closing thereof.

The invention further embodies manually operable devices for releasing or opening an outlet valve in the delivery bowl, the coin in passing through the operating mechanism sequentially rendering operative the manually operable devices and finally discharged into a coin receptacle, there being provided automatically operating devices for holding the controlling valve in either open or closed positions.

With the above and other objects in view that will become apparent as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a side elevational view of the gasoline pump attachment that is arranged in proximity of a delivery receptacle or bowl with the covering or casing therefor removed and showing the three plunger rods for operating the same,

Figure 2 is a rear elevational view of the device showing the coin detector cylinder for delivering the coin to the cylinder that effects opening movement of the valve to control the supply of gasoline to the delivery bowl and a third cylinder to receive the coin from the aforesaid cylinder and operating to open the valve for delivering gasoline from the delivery bowl,

Figure 3 is a vertical longitudinal sectional view through the three cylinders,

Figure 4 is an end elevational view showing the pipe for returning the overflow of gasoline in the delivery bowl to the storage tank,

Figure 5 is a vertical cross-sectional view taken on line V—V of Fig. 2 showing the cup or bucket in the gasoline return pipe to effect releasing or closing movement of the valve that controls delivery of gasoline to the delivery bowl,

Figure 6 is a horizontal sectional view taken on line VI—VI of Fig. 2 showing the coin detector cylinder and the lever to effect release of a false or counterfeit coin,

Figure 7 is a side elevational view, partly in section showing the piston rod that opens the valve to deliver gasoline to the delivery bowl extended and operating the dog to release the same from the piston rod that operates the valve to deliver gasoline to the customer,

Figure 8 is a fragmentary side elevational view showing the tensioned dog for holding the piston rod for the delivery valve in open position, and

Figures 9 and 10 show detail sectional views of the two control cylinders for operating the valve.

The operating mechanism for the gasoline pump is encased in a box structure or the like and the direct supporting means for the operating mechanism includes a wall 1 of plate formation carrying an angle wall having one side 2 thereof secured as at 3 to the wall 1 with the end wall 4 extending at right angles and aligned with the operating mechanism as shown in Fig. 6. The two wall members are further connected by angle braces 5.

Three horizontal cylinders arranged in parallel spaced relation and numbered 6, 7 and 8 are secured as at 9 upon the wall 1, the cylinder 6 acting as a coin detector, the cylinder 7 operating a valve to cause the flow of gasoline from a supply tank to a de-

livery bowl while the cylinder 8 operates the valve for controlling the delivery of the gasoline from the bowl to a purchaser. The delivery bowl, not illustrated, being in the form of a glass container commonly used, incloses an overflow pipe 10 illustrated by dotted lines in Fig. 5 and is connected to a return pipe 11 that has a pipe connection 12 with the main supply tank, the return pipe 11 being vertically disposed and supported by the bracket 13 upon the walls 1 and 2 as indicated by the reference numeral 14 in Figs. 4 and 5.

The overflow pipe 10 in the delivery bowl is vertically adjustable to determine the quantity of gasoline to be delivered to the bowl and discharged therefrom and the operation of the mechanism being coin controlled, the overflow pipe may be adjusted to dispense quantities of gasoline to the value of half-dollar or dollar coins. A coin is inserted in the opening 15 formed in the wall 2 and directed into the coin chute 16 supported as at 16^a upon the inner face of the wall 1. The coin passes downwardly in the chute 16 and enters the cylinder 6 through the slotted opening 17.

A cap 18 closes the outer end of the cylinder 6 and confines a coil spring 19 that engages at its inner end the piston members 20 and 21 to normally force the same in a direction toward the wall 4 of the supporting frame. The piston members 20 and 21 are spaced as at 22 and so retained by the laterally positioned key 23 shown more clearly in Fig. 6, which key is slidable in the longitudinal slot 24 formed in the cylinder 6. When the piston members 20 and 21 are at their limit of retracted movement the space 22 therebetween is aligned with the chute 16 and in position to receive a coin from the chute. As shown in Fig. 3, the piston member 21 is provided with a recess 25 closed at its outer end by a screw plug 26, the bottom wall of the recess and screw plug having aligned openings through which a pin 27 is slidable, that portion of the pin within the recess being surrounded by a coil spring 28 that engages the bottom wall of the recess and the collar 29 fixed to the pin for normally holding the outer end of the pin in a position to project slightly beyond the outer face of the screw plug 26. A plunger 30 slidable through the end wall 4 of the supporting frame is pivotally connected as at 31 to a cam 32, said cam being pivotally supported as at 33 upon the bracket 34 that is anchored as at 35 to the walls 1 and 2 of the supporting frame. A lever 36 pivotally supported upon the pin 33 above the cam 32 carries an operating handle 37 freely extending through registering slotted openings 38 in the walls 1 and 2 of the supporting frame.

When a coin is received in the space 22

between the piston members 20 and 21, the plunger rod 30 is operated to cause the cam 32 to move upon the pivot pin 33 and engage the pin 27 and plunger member 21 to move the two plunger members in the cylinder 6 against the tension of the spring 19. The pin 27 is slightly projected from the piston member 21 to frictionally engage the coin to hold the coin between the two piston members and to pass safely over the slotted opening 39 in the bottom wall of the cylinder 6 and to place the coin above the slotted opening 40 that communicates with the coin chute 41 for delivering a coin from the cylinder 6 into the cylinder 7 through the slotted opening 42 in the upper side of the latter cylinder. When the coin has been disposed over the opening 40 in the cylinder 6, pressure on the plunger rod 30 is relieved and the piston members may be retained in their projected position against the tension of the spring 19 by the lever 36 engaging the outer end of the piston member 21, the pin 27 at this time being disengaged from the coin by the spring 28 with the coin dropping through the chute 41 into the cylinder 7. In the event of the use of a false or counterfeit coin, such as a washer or the like, the pin 27 would be positioned in the central opening of the washer and when the piston members 20 and 21 were projected, the false coin or washer would drop into the first slotted opening 39, and to eliminate clogging of the machine, pressure on the plunger rod 30 is relieved and by operating the lever 36 to vibrate the piston members, the false coin or washer would be shaken loose and dropped from the cylinder 6 through the slotted opening 39.

The cylinder 7 being coin controlled in its operation, the end thereof adjacent the wall 4 of the supporting frame has a bearing plug 43 secured therein and provided with an axial opening for the plunger rod 44 that is tensioned as at 45. A piston head 46 slidably in the cylinder 7 is retained against rotary movement by the stud screw 47 projecting through the slotted opening 48 in the wall of the cylinder as shown in Fig. 9 and said piston head 46 is provided with a central opening aligned with the tubular piston rod 49 that slidably extends through the block 50 secured in the outer end of the cylinder. A coil spring 51 surrounding the tubular piston rod 49 and engaging the piston head 46 and block 50 retains the piston head at its limit of inward movement within the cylinder that is occasioned by the stop lug 52 projecting laterally of the tubular piston and engaging the outer face of the block 50.

As diagrammatically illustrated in Fig. 2, the outer projecting end of the tubular piston rod 49 has a lever connection 53 with a valve in the case 54, said valve case having a lead-in pipe 55 from a main storage gaso-

line tank and an outlet pipe 56 to a gasoline dispensing bowl. When the coin is delivered into the space 57 between the block 43 and piston head 46 in the cylinder 7, the same is engaged by the plunger rod 44 as shown in Fig. 9 to effect movement of the piston head and piston rod for operating the valve in the case 54. The coin C is carried forwardly by the plunger rod 44 and is positioned over the outlet slot 58 in the lower side of the cylinder 7 and being discharged through said slot enters the cylinder 8 through the slot 59 in the upper side thereof in a manner to be presently described.

10 the outlet slot 58 in the lower side of the cylinder 7 and being discharged through said slot enters the cylinder 8 through the slot 59 in the upper side thereof in a manner to be presently described.

15 It being desired to retain the tubular piston rod 49 in its extended position with the valve in the case 54 open to supply gasoline to the delivery bowl, devices are provided for engaging the piston rod to hold the same extended and include the provision of a side opening 60 in the piston rod 49 as shown in Fig. 3 to receive the lug 61 upon the lever 62, shown more clearly in Fig. 4, the lever 62 being pivotally mounted as at 63 upon the outer end of the cylinder block 50 and downwardly spring pressed as at 64 to cause the lug 61 constantly to ride over the side of the piston rod 49. With the tubular piston rod 49 extended and with the lug 61 upon the lever 62 received in the opening 60 in the piston rod, the valve in the case 54 is retained in an open position and gasoline is permitted to flow from the main supply tank to the delivery bowl, while the piston rod 49 is retained in a projected position.

20 With the piston rod so disposed, the piston 46 is positioned at the outer side of the lower coin slot 58 and when the plunger rod 44 is retracted by the spring 45, the coin is permitted to drop from the cylinder 7 through the slots 58 and 59 into the cylinder 8.

Devices are associated with the lever 62 to elevate the outer end thereof for disengaging the lug 61 from the piston rod 49 to permit the spring 51 to move the piston head 46 toward the end block 43 for closing the valve in the case 54 and cut off the supply of gasoline to the delivery bowl, such devices being operated by the gasoline in the bowl entering the overflow pipe 10 and passing through the return pipe 11 to the main supply tank. As shown in Fig. 7, the connection 65 between the overflow pipe 10 and return pipe 11 is provided with a side opening bearing 66 that pivotally supports as at 67, a lever 68, the outer extending end of the lever 68, as shown in Fig. 4 having a link connection 69 with the outer end of the lever 62. As shown in Fig. 5, a link rod 70 is carried by the inner end of the lever 68 within the return pipe 11, the link rod 70 passing downwardly through the bucket 71 and angularly bent at its lower end to engage the bottom wall of the bucket with the lower bent end of the link rod positioned

between the spaced lugs 72 that receive a cross pin 73 to retain the bucket in position upon the link rod. A horizontally positioned slotted opening 74 is formed in the side wall of the bucket 71 adjacent the bottom wall as shown in Fig. 5 and when the bucket is in its elevated position the slotted opening is closed by the wall of the return pipe 11.

With gasoline delivered to the dispensing bowl through the supply pipe 56 shown in Fig. 2 and rising above the overflow pipe 10 will flow into the latter and through the return pipe 11 and pipe 12 to the main supply tank. The gasoline in passing through the return pipe 12 will first be caught by the bucket 71 and the weight of the gasoline within the bucket will cause the latter to be lowered to operate the lever 68 and through the link connection 69 with the lever 62, elevate the outer end of the lever 62 to disengage the lug 61 from the opening 60 in the tubular piston rod 49, the spring 51 moving the piston rod into the cylinder 7 and being limited by the lug 52 engaging the outer face of the block 50, such movement causing the lever 53 carried by the outer end of the piston rod 49 to operate the valve in the case 54 to shut off the supply of gasoline to the dispensing bowl. The bucket 71 being lowered through the return pipe 11 permits the overflow of gasoline to pass through the slotted opening 74 in the side wall thereof to be returned to the main supply tank so that only a predetermined quantity of gasoline controlled by the authorized adjustment of the overflow pipe 10 will remain in the dispensing bowl.

An outlet valve is provided for the gasoline dispensing bowl and the operation thereof is effected by devices associated with the cylinder 8, said cylinder being of a construction and housing a piston and piston rod similar to the cylinder 7, the inner end of the cylinder 8 having a centrally apertured block 75 set therein with the outer end thereof closed by the centrally apertured block 76. The plunger rod 77 slidable through the end wall 4 of the supporting frame passes through the apertured block 75 and is spring pressed as at 78. The centrally apertured piston head 79 carries a tubular piston rod 80 slidable through the end block 76, said piston rod 80 being surrounded by the coil spring 81 for moving the piston head 79 toward the block 75, such movement being limited by the bearing 82 for the arcuate arm 83 secured to the outer projecting end of the tubular piston rod 80 as shown in Figs. 3 and 8. The piston head 79 being reciprocable within the cylinder 8, rotary movement thereof is prevented by the stud screw 47^a extending through the slotted opening 48^a in the cylinder 8 and shown in detail in Fig. 10.

When the coin C passes through the slotted opening 59 in the side of the cylinder 8, the same is received in the space 84 between the end block 75 and piston head 79 and in position to render the plunger rod 77 operative. The projecting end of the tubular piston rod 80, as diagrammatically illustrated in Fig. 2 effects the opening movement of the outlet valve for the dispensing bowl, a lever 85 pivotally connected to the outer end of the piston rod 80 being connected with a valve in the valve case 86, which valve case has an inlet pipe 87 leading from the dispensing bowl and an outlet pipe 88 for delivering the gasoline to a purchaser.

Devices are provided for holding the dispensing valve in an open position and includes a bracket 89 supported upon the wall 1 of the supporting frame adjacent the outer end of the cylinder 8 and upon which the dog 90 is pivotally mounted as at 91, said dog being provided on one end thereof with a cam arm 92 while the other end is formed with a latch 93. As shown in Fig. 6, a coil spring 94 encircles the pivot pin 91 with one end thereof engaging the bracket 89 while the other end of the spring engages the dog 90 adjacent the latch 93 for normally influencing the latch in a direction toward the piston rod 80 and causing the cam arm 92 of the dog to ride over the piston rod 49 of the cylinder 7. A notch 95 formed in the outer end of the piston rod 80 is adapted to receive the latch 93 when the piston rod is projected to hold the latter in its extended position with the valve in the case 86 open for dispensing gasoline from the bowl. When the tubular piston rod 80 is held in its projected position by the dog 90, the coin in the space 84 between the block 75 and piston 79 is disposed over the coin outlet 84a by being forwardly projected by the plunger rod 77 and drops through said slot when the plunger 77 is released. The outlet valve for the dispensing bowl remains in an open position after the contents of the bowl have been emptied and is moved to its closed position during the subsequent operation of the mechanism during the following purchase of gasoline. A coin being received in the detector cylinder 6 and moved into the cylinder 7 for operating the valve in the case 54 that delivers gasoline to the dispensing bowl, operation of the piston rod 49 effects the release of the piston rod 80 and the closing of the valve in the case 86 that controls the discharge of gasoline from the dispensing bowl. As shown in Fig. 3, a button 96 carried by the piston rod 49 engages the cam 92 of the dog 90 for moving the dog upon its pivot pin 91 against the tension of the spring 94 to disengage the latch 93 from the notch 95 in the piston rod 80, the spring 81 drawing the piston rod into the cylinder 8 and closing the valve in the case 86. In the event that

the bucket 71 in the return pipe 11 fails to operate the lever 62 shown in Fig. 4 for releasing the valve that controls the supply of gasoline from the main storage tank to the dispensing bowl, the projection of the piston rod 80 causes the arcuate arm 83 to engage the lever 62, as will at once be evident from an inspection of the drawings to positively elevate the lever 62 and permit the spring 51 to retract the piston rod 49 into the cylinder 7 and close the supply valve in the case 54.

From the above detail description of the construction and operation of the invention, it is believed that the full import thereof will at once be understood, it being noted that a false or counterfeit coin will at once be detected in the first coin receiving cylinder 6 and may readily be removed or discharged therefrom before passing through either of the cylinders 7 or 8. Each of the cylinders are coin controlled in their operation, the operation of the mechanism in the cylinder 7 effecting the supply of gasoline from a main storage tank to the dispensing bowl while the operation of the mechanism associated with the cylinder 8 closes the supply valve and opens the valve that permits discharge of the gasoline in the dispensing bowl to the purchaser. It is to be understood that gasoline may be delivered from the main storage tank to the dispensing bowl in any suitable manner, such as by air pressure or pump mechanism, the operation of such devices being controlled by the piston rod 49. Also, the piston rod 49 may control electric switches, controlling gears, a pump handle or lever and any form of mechanism that is capable of being locked, and released by projecting movement of the piston rod 49.

While there is herein shown and described the preferred embodiment of the present invention, it is nevertheless to be understood that minor changes may be made therein without departing from the spirit and scope of the invention as claimed.

What is claimed is:—

1. In a self-service gasoline pump attachment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge, said bowl having an overflow pipe therein communicating with a return pipe leading to the storage tank, means for holding the supply mechanism for the bowl in an open position, and means in the return pipe rendered operative by overflow gasoline passing therethrough and associated with the supply mechanism to release the latter.

2. In a self-service gasoline pump attach-

ment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge and sequentially rendered operative by a coin passing through the mechanism, said bowl having an overflow pipe therein communicating with a return pipe leading to the storage tank, means for holding the supply mechanism for the bowl in an open position, and means in the return pipe rendered operative by overflow gasoline passing therethrough and associated with the supply mechanism to release the latter.

3. In a self-service gasoline pump attachment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge, said bowl having an overflow pipe therein communicating with a return pipe leading to the storage tank, means for holding the supply mechanism for the bowl in an open position, means in the return pipe rendered operative by overflow gasoline passing therethrough and associated with the supply mechanism to release the latter, and said overflow pipe being adjustable in the bowl for dispensing various quantities of gasoline and unaffecteding the operation of the releasing means for the supply mechanism.

4. In a self-service gasoline pump attachment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge and sequentially rendered operative by a coin passing through the mechanism, said bowl having an overflow pipe therein communicating with a return pipe leading to the storage tank, means for holding the supply mechanism for the bowl in an open position, means in the return pipe rendered operative by overflow gasoline passing therethrough and associated with the supply mechanism to release the latter, and said overflow pipe being adjustable in the bowl for dispensing various quantities of gasoline and unaffecteding the operation of the releasing means for the supply mechanism.

5. In a self-service gasoline pump attachment, the combination with a main storage tank, a dispensing bowl and means for de-

livering gasoline from the tank to the bowl, of coin controlled mechanism for controlling the supply and discharge of gasoline to and from the bowl, said mechanism including separately operable devices for the supply and discharge, said bowl having an overflow pipe therein communicating with a return pipe leading to the storage tank, means for holding the supply mechanism for the bowl in an open position, a bucket suspended in the return pipe and connected to the holding means and adapted to operate the latter when weighted with overflow gasoline.

6. In a self-service gasoline pump attachment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge and sequentially rendered operative by a coin passing through the mechanism, said bowl having an overflow pipe therein communicating with a return pipe leading to the storage tank, means for holding the supply mechanism for the bowl in an open position, a bucket suspended in the return pipe and connected to the holding means and adapted to operate the latter when weighted with overflow gasoline.

7. In a self-service gasoline pump attachment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge, said bowl having an overflow pipe therein communicating with a return pipe leading to the storage tank, means for holding the supply mechanism for the bowl in an open position, a bucket suspended in the return pipe and connected to the holding means and adapted to operate the latter when weighted with overflow gasoline, and said bucket cooperating with the wall of the return pipe to retain gasoline therein and being constructed to discharge the gasoline for return to the storage tank when lowered by the weight of the gasoline below the lower end of the return pipe.

8. In a self-service gasoline pump attachment, the combination with a main storage tank, a dispensing bowl and means for delivering gasoline from the tank to the bowl, of coin controlled mechanism for controlling the supply and discharge of gasoline to and from the bowl, said mechanism including separately operable devices for the supply and discharge and sequentially rendered

operative by a coin passing through the mechanism, said bowl having an overflow pipe therein communicating with a return pipe leading to the storage tank, means for holding the supply mechanism for the bowl in an open position, a bucket suspended in the return pipe and connected to the holding means and adapted to operate the latter when weighted with overflow gasoline, and 5 said bucket cooperating with the wall of the return pipe to retain gasoline therein and being constructed to discharge the gasoline for return to the storage tank when lowered by the weight of the gasoline below the lower end of the return pipe.

9. In a self-service gasoline pump attachment, the combination with a main storage tank, a dispensing bowl and means for delivering gasoline from the tank to the bowl, 10 of coin controlled mechanism for controlling the supply and discharge of gasoline to and from the bowl, said mechanism including separately operable devices for the supply and discharge, said bowl having an overflow pipe therein communicating with a return pipe leading to the storage tank, means for holding the supply mechanism for the bowl in an open position, a bucket suspended in the return pipe and connected to the holding means and adapted to operate the latter when weighted with overflow gasoline, said bucket having a slotted opening adjacent its bottom wall normally closed by the wall of the return pipe when the bucket is elevated 15 and the supply mechanism is open and said bucket being moved downwardly by the weight of gasoline therein to release the holding means and dispose the bucket slot below the lower end of the return pipe for returning the overflowing gasoline to the storage tank.

10. In a self-service gasoline pump attachment, the combination with a main storage tank, a dispensing bowl and means for delivering gasoline from the tank to the bowl, 20 of coin controlled mechanism for controlling the supply and discharge of gasoline to and from the bowl, said mechanism including separately operable devices for the supply and discharge and sequentially rendered operative by a coin passing through the mechanism, said bowl having an overflow pipe therein communicating with a return pipe leading to the storage tank, means for holding the supply mechanism for the bowl in an open position, a bucket suspended in the return pipe and connected to the holding means and adapted to operate the latter when weighted with overflow gasoline, said 25 bucket having a slotted opening adjacent its bottom wall normally closed by the wall of the return pipe when the bucket is elevated and the supply mechanism is open and said bucket being moved downwardly by the weight of gasoline therein to release the

holding means and dispose the bucket slot below the lower end of the return pipe for returning the overflowing gasoline to the storage tank.

11. In a self-service gasoline pump attachment, the combination with a main storage tank, a dispensing bowl and means for delivering gasoline from the tank to the bowl, of a series of independently operable coin controlled devices for operating a valve to deliver gasoline to the bowl, means for retaining the valve in an open position, operating a valve to discharge gasoline from the bowl, means for retaining the discharge valve in an open position, and said last 50 named means being rendered inoperative upon operation of the valve that delivers gasoline to the bowl.

12. In a self-service gasoline pump attachment the combination with a main storage tank, a dispensing bowl and means for delivering gasoline from the tank to the bowl, of a series of cylinders, a piston in each cylinder, a plunger rod for manually operating each piston, said cylinders being arranged and provided with coin passage slots 55 for the sequential passage of a coin therethrough received in the first cylinder, means associated with the piston in the first cylinder to deliver a coin to the second cylinder, the other cylinders being coin controlled in their operation, means operated by the piston of the second cylinder for delivering gasoline from the storage tank to the bowl, and means operated by the piston of the last cylinder 60 for delivering gasoline from the bowl to the purchaser.

13. In a self-service gasoline pump attachment the combination with a main storage tank, a dispensing bowl and means for delivering gasoline from the tank to the bowl, of a series of cylinders, a piston in each cylinder, a plunger rod for manually operating each piston, said cylinders being arranged and provided with coin passage 65 slots for the sequential passage of a coin therethrough received in the first cylinder, means associated with the piston in the first cylinder to deliver a coin to the second cylinder, the other cylinders being coin controlled in their operation, means operated by the piston of the second cylinder for delivering gasoline from the storage tank to the bowl, means for holding the piston in its extended operative position, means affected by the overflow of gasoline from the bowl to release the holding means, and means operated by the piston of the last cylinder for delivering gasoline from the bowl to the purchaser.

14. In a self-service gasoline pump attachment the combination with a main storage tank, a dispensing bowl and means for delivering gasoline from the tank to the bowl, of a series of cylinders, a piston in each cyl- 130

means carried by the piston of the second cylinder to release the holding means for the piston of the last cylinder, and a mechanical instrumentality carried by the piston of the last cylinder to positively engage and release the holding means for the piston of the second cylinder to insure the closing of the delivery valve when the discharge valve for the bowl is opened.

19. The combination with a gasoline pump, wherein means is provided for elevating a quantity of gasoline from a storage tank into a bowl, wherein means is further provided to control the elevation of the gasoline from the tank to the bowl by said elevating means, and wherein overflow means is provided for returning to the storage tank such gasoline as is elevated to the bowl in excess of said quantity, of coin-controlled manually operable means for actuating said controlling means to cause the elevation of the gasoline to the bowl, means to automatically operate said controlling means for stopping further elevation of gasoline to the bowl upon occurrence of an overflow of excess gasoline from the bowl, and a second coin-controlled means to receive the coin from the first named coin controlled means and manually operable for effecting dispensation of gasoline from the bowl to a desired point of discharge.

20. An attachment for gasoline pumps, wherein means is provided to elevate gasoline from a storage tank into a bowl, wherein means is provided to control the operation of said elevating means, and wherein means is provided for controlling the dispensation of the gasoline from the bowl, comprising manually operable coin-controlled means for operating said dispensation controlling means to permit dispensation of gasoline from the bowl, and manually operable coin-controlled means to operate the controlling means for the elevating means, said last named manually operable means being adapted when operated to deliver the controlling coin to the first named manually operable means.

21. The combination with a gasoline pump, wherein means is provided for transferring gasoline from a storage tank and delivering a quantity thereof to a desired point of discharge, and wherein two control elements are provided to control the transfer and delivery of the gasoline from the tank to said point of discharge, of coin-controlled means manually operable to render one of said control elements operative and to deliver the coin therefrom, means to

automatically latch said one control element in operative position, means to automatically release said latch means when a predetermined quantity of gasoline has been transferred from the tank, means to automatically render said one control element inoperative upon release of said latch means, and a second coin-controlled means to receive the coin delivered from the first coin-controlled means and manually operable to render the other control element operative.

22. The combination with a gasoline pump, wherein means is provided for transferring gasoline from a storage tank and delivering a quantity thereof to a desired point of discharge, and wherein two control elements are provided to control the transfer and delivery of the gasoline from the tank to said point of discharge, of coin-controlled means manually operable to render one of said control elements operative and to deliver the coin therefrom, means to automatically latch said one control element in operative position, means to automatically release said latch means when a predetermined quantity of gasoline has been transferred from the tank, means to automatically render said one control element inoperative upon release of said latch means, a second coin-controlled means to receive the coin delivered from the first coin-controlled means and manually operable to render the other control element operative and to deliver the coin therefrom, means to automatically latch said other control element in operative position, means to automatically release said latch means when a predetermined quantity of gasoline has been transferred from the tank, means to automatically render said one control element inoperative upon release of said latch means, a second coin-controlled means to receive the coin delivered from the first coin-controlled means and manually operable to render the other control element operative.

23. An attachment for gasoline pumps, wherein means is provided for transferring gasoline from a storage tank and delivering a quantity thereof to a desired point of discharge, and wherein two control elements are provided to control the transfer and delivery of the gasoline from the tank to said point of discharge, comprising manually operable coin-controlled means for operating one of said control elements, and manually operable coin-controlled means to operate the other control element, said first named manually operable means being adapted when operated to deliver the controlling coin to the second named manually operable means.

In testimony whereof I affix my signature.
GEORGE W. KECK.
